UNITED STATES PATENT OFFICE.

HARRY G. CALEF, OF HAVERHILL, MASSACHUSETTS.

PROCESS OF MAKING SHOES.

1,110,885.

Specification of Letters Patent. Patented Sept. 15, 1914.

Application filed April 13, 1914. Serial No. 831,357.

To all whom it may concern:

Be it known that I, HARRY G. CALEF, a citizen of the United States, residing at Haverhill, in the county of Essex and State of Massachusetts, have invented an Improvement in Process of Making Shoes, of which the following is a specification.

This invention relates to certain improvements in processes for making shoes, and 10 more particularly, to improvements in processes of making low cut, turned shoes of the kind known as "slippers" or "pumps."

In shoes of this character, the counter is relied on, practically wholly, to hold the 15 shoe from slipping at the heel when worn, so that it is desirable to have the edges of the upper, about the foot opening, fit or be drawn against the sides of the foot as closely as possible, when on the foot, and, to this 20 end, and to the end, also, that the appearance of the shoe, before it is worn, may be improved, it is desirable that these shoes be so made that the opposite edges of the upper will be drawn together as closely as 25 possible.

In shoes of the above type it is customary to employ a shank stiffener which extends from the rear end of the shoe to the front end of the shank, and it has further been 30 customary so to mold the heel part of the stiffener that it is convex on the under side, to correspond to the concaved recess formed in the base of the heel on the bottom of which the heel of the sole rests.

35 I have ascertained that in the manufacture of shoes of the above described character, employing in their construction, stiffeners, the heel portions of which are either flat, or are molded to conform to the 40 concavity of the heel, i. e., convex on their under side, certain difficulties are encountered which have an important effect on the final results which are secured. The more important of these is the difficulty in forming 45 a uniformly flat seat for the reception of the heel, and the difficulty in preventing the counter and sides of the upper from being spread outward when the heel is attached. The difficulty in forming, and the

50 frequent failure to form a level seat for the reception of the heel, is largely due to the fact that, when a shank stiffener is employed which is so molded that it is convex on the under side, the middle portion 55 of the heel of the sole is forced out beyond the level of its edge portion, so that, in the

beating-out process, this middle portion, which is highest, receives the main force of the blows of the beating-out hammer, instead of the edge portion. Also, if special pains is taken to pound down or level the inturned edge-portion of the counter, against which the edge of the heel is to rest, eventually it is found that such portion is not supported with sufficient firmness to enable this portion to be beaten down to a level surface. The result is that, in practically all such cases, the edge portion is not properly leveled.

Before attaching a wooden heel, the edge 70 portion of the heel of the sole is cut away, so that the edge of the heel may rest directly on the inturned edge of the upper and counter, and, consequently, if the heel seat formed by said inturned edge portion 75 is not properly leveled the edge of the heel will not bear against the heel seat at all points, so that a tight joint will not be formed therebetween when the heel is attached, making it necessary that these parts 80 be pressed together at a subsequent operation, which usually consists in forcing the parts together by a press, or other suitable means, with the result that the sides of the shoe opening are frequently spread and the 85 tread of the shoe is affected to an objectionable extent. This result is caused through the fact that, when an open joint between the rear portion of the heel and the heel seat is to be pressed together, the 90 front end of the heel acts as a pivot for the sole, so that, as the portion in the rear is pressed down, the forepart of the sole will be pressed up, causing the sides of the 95 upper to be spread apart and the ball of the sole to be moved out of the plane of the top lift, so that the shoe no longer treads properly.

The object of my invention is to provide 100 an improved method of manufacturing shoes of the above described type, whereby the difficulties above referred to may be obviated, and whereby, when the heel is attached, the counter may be drawn inwardly, so that it will fit more closely about the 105 heel of the wearer, and the sides of the upper will be drawn together more closely than before.

I accomplish this object, primarily, by 110 providing a form of shank stiffener, which, instead of being molded so that it is convex on the under side, is convex on the up-

per side, so that the margin of the heel seat is supported above the level of the middle portion of the sole during the beating-out operation, thereby enabling the heel seat to be properly leveled and the difficulties hereinbefore noted to be avoided, and further enabling the counter to be drawn inward when the heel is attached.

For a more complete understanding of the means and method which I employ, reference is made to the accompanying drawings, forming a part of this specification, in which—

Figures 1, 2, 3, 5 and 6 are transverse sectional views through the heel-portion of a shoe showing the same in different stages of the process of manufacture. Fig. 4 is a perspective view of the heel portion of the shoe just before the heel is attached. Fig. 7 is a longitudinal central section, and Fig. 8 a side elevation of a finished shoe, and Figs. 9 and 10 are edge-elevations and longitudinal sectional views respectively of the shank stiffener which I employ.

In the drawing, *a* indicates an ordinary wood heel, having a concave base-portion and *b* the outer-sole of the shoe to which the upper *c*, the counter *d*, and the lining *e*, are attached by sewing when the shoe is turned wrong-side out, such shoes being usually made by the turn process.

A shank stiffener, *f*, is provided, which is usually made of leather-board, or similar flexible stiffening material, said stiffener being arranged on the inner side of the outer-sole and extended from the rear end thereof forwardly to the front end of the shank.

According to my invention, instead of molding the heel-portion *f'*, of the stiffener so that it is convex on its under side, I mold the same so that it is convex on the upper side and therefore concave on the under side, for the purpose which will now be explained.

After the shoe has been sewed and turned, the stiffener *f* is inserted in the shoe, as shown in Fig. 1, and is secured to the sole by a nail *h*, which is driven through the middle portion of the heel parts thereof. This causes the edge portion of the stiffener to be pressed firmly against the edge-portion of the heel of the sole, and as the sole is then in temper and is much more easily bent than the stiffener, said edge-portion of the sole is pressed outwardly, as indicated in Fig. 2.

The shoe is relasted and leveled or beaten-out, and, when the heel seat is leveled, the pressure or blows of the hammer will be brought to bear principally on the edge portion of the sole, which is yieldingly supported above the middle portion thereof by the then upturned edge portion of the stiffener. As these edge portions are beaten down to the last the inturned edge of the

counter, which practically constitutes the heel seat, will be forced down firmly onto the edge portion of the stiffener and will be made level and uniform, and a sharp bend or shoulder will be formed therein at the edge of the stiffener, as indicated in Fig. 3. The shoe, which was previously in temper, is then permitted to dry on the last, so that the parts will approximately retain the shape in which they are thus held.

If a wood heel is to be attached, the edge portion of the sole is then cut away, so that the inturned counter portion directly therebeneath, at the point where it was sharply bent inward and leveled by the leveling process, is exposed, as shown in Fig. 4, and then the heel is placed in position thereon, so that its base edge bears directly against the sharp shoulder, or bend formed in the counter by the leveling process, as shown in Fig. 5.

It may be here noted that, when the forms of stiffener, which have been previously employed, are used, either the heel of the sole bears on the base of the heel entirely across the same, or it bears on the middle of the heel, so that the edge thereof is prevented from firmly engaging the edge of the heel seat. In the first instance, if the edge of the heel does not firmly engage the edge of the heel seat at every point around it, there is no tendency to close the joint tightly at such point, when the heel is attached, and, in the second instance, the middle portion of the sole will hold the heel seat and the heel edge out of contact, so that they will have to be drawn together. In doing this the counter will be spread open, so that, when the shoe is worn, it will not closely grasp the heel. Also, this spreading action will enlarge the whole opening of the shoe, and the sole is also likely to be swung so that it will not tread, as before explained.

When the form of stiffener, which is normally convex on the inner side or side opposite from the heel, is employed, while the heel of the sole will not be drawn inwardly at its middle portion by the stiffener to as great an extent as before relasting, yet it will be drawn in slightly, so that in practically all instances the middle portion of the sole will be held at some distance from the middle portion of the heel base, as indicated in Fig. 5.

With the parts thus arranged, a number of attaching nails *i* are driven through the stiffener and sole into the heel, causing the middle heel-part of the sole and of the stiffener to be drawn into the concave recess in the base of the heel and pressed firmly thereon, as shown in Fig. 6. As the edge of the heel is resting fairly on the heel seat at the beginning of the attaching operation, it follows that this operation will not

only force these edge portions firmly together, so as to form a tight joint, but will also cause said edge portion to be drawn or swung inward, thus causing the counter, the 5 inturned edge of which is clamped between the sole and stiffener, to be swung inwardly to a corresponding extent, as indicated in Fig. 6. The result is that the counter is firmly set in this indrawn position, not only 10 causing it to fit tightly about the heel of the wearer, but also acting to draw the sides of the upper about the shoe opening inward to a corresponding extent, materially decreasing the width of said opening, a result which 15 is greatly desired.

It may be noted in this connection, that, where the oppositely dished, or molded stiffener is employed, so that the heel part of the sole and stiffener conforms almost exactly to the concavity of the heel base before attachment, when the heel is attached, there is no inward bending of the sole and counter which would tend to swing the counter inward.

25 As the uniform and accurate leveling of the heel seat is made possible by the action of the stiffener in forcing the same outwardly and providing a suitable support therefor during the leveling process, and as 30 the heel seat and edge of the heel are closely drawn together by the attaching process, as previously explained, a continuous tight joint is formed between the heel and heel seat, which will be in a straight 35 line with the edge of the shank portion of the sole, as indicated in Fig. 8.

While the above described method and construction is particularly advantageous with shoes having wood heels, it is also advantageous with shoes to which leather or leather-board heels are attached, although perhaps not to such a marked degree, for the reason that, with heels of this class, the joint which is closed in the attaching operation is between the heel and sole, and not

between the heel and upper, the sole edge not being cut away as indicated in Fig. 4, so that the difficulties encountered are not as great.

I claim:

1. The method of making shoes which consists in yieldingly supporting the edge-portion of the heel-seat of the shoe above the level of the support for the middle portion of the heel of the sole and leveling said heel-seat edge-portion by forcing the same onto said yielding support. 50

2. The method of making shoes which consists in providing a flexible supporting plate, for the heel-seat of the shoe, concavely curved on its side next the seat to provide a yielding support for the edge-portion thereof above the level at which it supports the middle portion of the heel of the sole, and leveling said heel-seat edge-portion by forcing the same onto the edge-portion of said plate. 60

3. The method of making shoes which consists in yieldingly supporting the edge-portion of the heel-seat of the shoe above 70 the level of the middle portion of the sole by a flexible stiffener of flat material and molded so that it is concaved on its side next the heel-seat, leveling said heel-seat edge-portion by forcing the same onto the 75 edge-portion of the stiffener and then attaching the heel to the heel-seat and at the same time drawing the middle portion of the heel of the sole into the concavity in the base of the heel and bending inwardly the 80 edge-portion of the sole, and causing the counter to be drawn inwardly to contract the shoe opening.

In testimony whereof, I have signed my name to this specification, in the presence of 85 two subscribing witnesses.

HARRY G. CALEF.
